CLAIM

The ornamental design for a shoe charm post, as shown and described.

DESCRIPTION

FIG. 1 is a top isometric view of a shoe charm post, showing my new design;

FIG. 2 is a bottom isometric view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a bottom isometric view thereof, shown in a used condition affixed to a heart shaped charm shown in broken lines; and,

FIG. 10 is an isometric view of FIG. 9, shown in a used condition affixed to a shoe shown in broken lines.

The broken lines represent environment and a portion of the shoe charm post that form no part of the claimed design.
